(57) **CLAIM**

We claim the ornamental design for a toner reload kit, as shown and described.

DESCRIPTION

FIG. 1 is a front perspective view of a toner reload kit showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged view of the encircled portion in FIG. 8;

FIG. 10 is another bottom perspective view thereof; and, FIG. 11 is an enlarged view of the encircled portion in FIG. 10.

The evenly spaced broken lines immediately adjacent to the shaded areas and which define unshaded regions depict the bounds of the claimed design, while all other evenly spaced broken lines are directed to environment. The broken lines form no part of the claimed design.

The dot-dash broken lines encircling portions of the claimed design that are illustrated in enlargements form no part of the claimed design.

The “hp” lettering and icon forming part of the disclosure is a registered trademark of HP HEWLETT PACKARD GROUP LLC.
